UNITED STATES PATENT OFFICE.

FERDINAND LANG, OF COLORADO SPRINGS, COLORADO.

FURNACE-GRADE.

1,163,420.

Specification of Letters Patent.

Patented Dec. 7, 1915.

Application filed November 28, 1914. Serial No. 874,432.

To all whom it may concern:

Be it known that I, FERDINAND LANG, subject of the Czar of Russia, residing at Colorado Springs, in the county of El Paso and State of Colorado, have invented certain new and useful Improvements in Furnace-Grates, of which the following is a specification.

This invention relates to grates for furnaces, and its object is to provide a novel and improved form of grate bar structure which renders the same strong and durable and not liable to warp or sag.

A further object of the invention is to provide a novel and improved means, whereby the grate bars may be operated independently, a coupling being provided which enables any one of the grate bars to be disconnected from the operating means.

These objects are attained by means of a combination and arrangement of parts to be hereinafter described and claimed reference being had to the accompanying drawing, in which—

Figure 1 is a plan view of the grate; Fig. 2 is a cross section on the line A—B of Fig. 1; Fig. 3 is a cross section on the line C—D of Fig. 1; Fig. 4 is an elevation of the grate-operating mechanism; Fig. 5 is an end view of said mechanism, and Fig. 6 is an elevation of a coupling pin employed in connection with the grate-operating mechanism.

Referring specifically to the drawing, 9 denotes the ash-pit of the furnace, the same having an upstanding top flange 8 within which seats the fire-box 19. The ash-pit is provided with a door 10. The fire box may be round, square or otherwise shaped.

The grate bars are indicated at 1, the same having trunnions 3 and 3^a, respectively, at their ends, whereby they are rotatably supported. The ash-pit 9 has seats 2 for the trunnions, said seats being on a depending annular flange 2^a located at the center of the top of the fire box and extending around the opening over which the fire-pot 19 seats. Cross pins 3^b above the trunnions 3 at the rear ends of the grate bars hold said trunnions down on their seats. The trunnions 3^a at the front ends of the grate bars pass loosely through apertures in the flange 2^a and project outside the latter. In the fire pot are projecting lugs 4 for the mismatching parts of the grate.

The following grate-operating means are

provided: To the projecting end of each trunnion 3^a is connected a short rock-shaft 6, the latter being journaled in the side wall of the ash-pit 9 and its inner end having a 60 socket 5 to receive the end of the trunnion, said trunnion end and the socket being angular in cross section so that when the shaft is rocked, the grate is also rocked. Endwise separation of the shaft and the trunnion is 65 prevented by a cross pin 7 passing through the former adjacent to the inside of the ash-pit side wall as shown in Fig. 2. To each rock-shaft is connected a crank or rocker arm 11. The connection is made by means 70 of a pin 12 running through the rock shaft and the crank, said pin being threaded and provided with a flat head, as shown in Fig. 6, so that it can be readily removed without the use of a tool. The pins are made removable 75 in order that any one of the cranks may be uncoupled from its shaft, for a purpose to be presently described. The cranks are connected by an operating bar 13 which latter is connected at one end by a link 14 80 to a hand lever 15 supported by a bracket 18 on the ash-pit 9. The cranks are heavier at the top than at the bottom to counterbalance the latter, to which the bar 13 is connected.

Upon operating the hand lever 15 back 85 and forth, the grate bars 1 are shaken, the motion of the lever being transmitted to the trunnions 3^a by the link 14, the bar 13, the cranks 11 and the shafts 6. The grate bars can also be dumped by pushing or pulling 90 the hand lever back as far as it will go. The grate can also be inverted without dumping the fire. This is done by raking the fire over to one side, and then removing the pins 12 from the cranks 11 of the grate 95 bars on which the fire rests to uncouple said grate bars from the operating mechanism. The other grate bars can then be inverted, after which the coupling pins are replaced, and the fire is raked back on the clean grate 100 bars, and then taking out the coupling pins from the cranks of the grate bars the fire is now on, the grate bars free of the fire are inverted, and more coal can be added to the fire. All the grate bars can be dumped or 105 inverted simultaneously by letting all the coupling pins remain.

The ash-pit 9 carries a pivoted latch 16 for locking the hand lever 15, said latch being shaped to straddle the lever as shown in 110 Fig. 1. Upon swinging the latch clear of the lever, the latter may be actuated to op-

erate the grate bars as hereinbefore described.

The grate bars are solid throughout their center along their entire length, and they are also thicker at the middle than at the edge, the thickness gradually and uniformly decreasing longitudinally and transversely. This stiffens the bars, and they are not liable to warp or sag. The grate bars can also be reversed if they become worn on one side, as their top and bottom portions are counterparts.

I claim:—

1. The combination with a furnace having a depending annular flange at the bottom of the fire box; of grate bars extending across the flange and having end trunnions, the flange having seats for the trunnions and apertures through which the trunnions on the front ends of the grate bars loosely pass, cross pins above the trunnions at the rear ends of the grate bars, rock shafts journaled in the side wall of the ash pit of the furnace in axial alinement with the trunnions of the respective grate bars and having sockets in their inner ends in which the trunnions on the front ends of the grate bars seat and are coupled to turn with said rock shafts, cross pins carried by the rock shafts adjacent to the side wall of the ash pit for locking the rock shafts against endwise movement in a direction to become disengaged from the trunnions of the grate

bars, cranks on the rock shafts on the outside of the ash pit, an operating bar connecting the cranks, and actuating means for said bar.

2. The combination with a furnace having a depending annular flange at the bottom of the fire box; of grate bars extending across the flange and having end trunnions, the flange having seats for the trunnions and apertures through which the trunnions on the front ends of the grate bars loosely pass, rock shafts journaled in the side wall of the ash pit of the furnace in axial alinement with the trunnions of the respective grate bars and having sockets in their inner ends in which the trunnions on the front ends of the grate bars seat and are coupled to turn with said rock shafts, cross pins carried by the rock shafts adjacent to the side wall of the ash pit for locking the rock shafts against endwise movement in a direction to become disengaged from the trunnions of the grate bars, cranks on the rock shafts on the outside of the ash pit, an operating bar connecting the cranks, and actuating means for said bar.

In testimony whereof I affix my signature in presence of two witnesses.

FERDINAND LANG.
